UNITED STATES PATENT OFFICE.

ADAM C. WILLIAMS, OF RAVENNA, OHIO.

DESIGN FOR A TOY BANK.

SPECIFICATION forming part of Design No. 30,076, dated January 31, 1899.

Application filed December 28, 1898. Serial No. 700,563. Term of patent 7 years.

To all whom it may concern:

Be it known that I, ADAM C. WILLIAMS, a citizen of the United States, residing at Ravenna, in the county of Portage and State of Ohio, have invented and produced a new and original Design for Toy Banks, of which the following is a specification, reference being had to the accompanying drawings, illustrating the same.

10 This invention has relation to a certain new and original design for toy banks; and it consists in the novel configuration and arrangement of the parts, so as to represent a multi-storied building, as hereinafter described, and 15 illustrated in the accompanying drawings.

Figure I is a front view of my bank; Fig. II, a side view; Fig. III, a plan view.

The leading characteristic of my design consists in the use of an open-work or grill 20 design in order to represent the windows and exterior walls of a building and relief-work to represent cornices, window-sills, and other exterior ornamentation of a building.

By reference to the drawings it will be seen 25 that my bank is octagonal in shape, so that from whatever point it is viewed three sides are visible, as A, B, and B', or B', C', and D'.

Referring to the drawings, the side A of the bank is designed to represent the front of a 30 building. Open-work or grill design is used to give the appearance of many tiers of windows. A horizontal rib is formed under every pair of open spaces or windows to represent sills therefor.

35 In the center, at the bottom of the side A, an arched entrance E is represented by means of an exterior curved rib. The part of the design inclosed by this arched rib is recessed, so as to form a vestibule. By an arrangement 40 of ribs and open spaces the entrance is given the appearance of having a transom extending across the top and three arched doorways. A pillar e stands on each side of the entrance and fits under a cornice or ledge F, which 45 runs across the front, immediately above the entrance.

In the center, at or near the top of the front, is a panel for any suitable word or inscription.

The configuration of the opposite side A' (not shown) is the same as that of the side A.

The configuration of sides B and B', Fig. I, D', Fig. II, and D (not shown) is identical. A single tier of open spaces occupies the center of each side to represent windows. Under each open space or window an exterior rib is formed, so as to make a sill therefor. The top of each of these sides is pointed to conform to the gabled corners of the roof. A cornice or ledge F' extends across each side, 55 corresponding to the ledge F on the side A.

The design of the side C', Fig. II, and the side C (not shown) is similar to that of B' and D', as described, with the substitution of rounded tops to conform to the curved edge 60 of the roof above the sides C and C'.

The main portion of the roof consists of three curved ridges G, G', and G''. The center one, G, is surmounted by a fluted or corrugated cupola II. This cupola is capped by a 70 sphere.

The edge of the roof above the sides A and A' is arched in the middle, then horizontal from a distance from each end of the arched portion, and then slopes down to the gabled 75 corners over the sides B, B', D, and D'. The edge of the roof over the sides C and C' is arched.

The portion of the roof joining the immediately-opposite gables is flat and diamond 80 shape in plan. A cornice extends around all sides at the edge of the roof.

What I claim is—

The design for a toy bank, substantially as herein shown and described. 85

Signed by me, at Ravenna, Ohio, this 16th day of December, 1898.

ADAM C. WILLIAMS.
